UNITED STATES PATENT OFFICE.

GUSTAV H. KLOEHS, OF PHILADELPHIA, PENNSYLVANIA.

PIPE-ORGAN CONTROL.

Application filed February 6, 1924. Serial No. 690,357.

My invention relates to improvements in pipe organs, and it consists of the constructions, combinations and arrangements herein described and claimed.

5 An object of the invention is to provide mechanism by means of which the sounding of organ pipes is effectively controlled and with dispatch, by reason of the fact that the operating means between the pipes and the 10 organ keys is of a very simple nature.

Another object of the invention is to provide an improved organ control which consists largely of relay and chest actions which cooperate in such a manner as to practically 15 constitute one part, said chest actions also being associated with a certain switch board action, the functions of which are necessary for the proper operation of the aforesaid relay and chest actions.

20 A further object of the invention is to provide an organ control in which the amount of mechanism between a given organ pipe and the operating key thereof is reduced to a minimum so that the response 25 at the pipe upon the depression of the key will be as prompt as possible and without bringing into operation any more than the least number of elements possible.

Other objects and advantages will appear 30 from the following specification reference being had to the accompanying drawings, in which—

Figure 1 is a diagram illustrating the 35 organ control as applied to an octave of keys and pipes.

Figure 2 is a perspective view of a portion 40 of the relay action which is directly associated with the keys.

Figure 3 is a detail perspective view of the contact wire block of one of the relays.

Figure 4 is a perspective view of the bridge which carries the block in Figure 3.

Figure 5 is a perspective view of the yoke which limits the raising movement of the 45 pneumatic which carries the contactor.

Figure 6 is a longitudinal section of one of the relays.

Figure 7 is a cross section of the chest 50 action at any one of the organ pipes, this view being readily identified with the diagrammatic illustration at the organ pipes in Figure 1.

Figures 8, 9 and 10 are perspective views 55 of details of one of the electro-pneumatic valves in the chest action.

Figure 11 is a perspective view of a portion of the switch board action.

Figure 12 is a detail perspective view of the pivoted contactor.

Figure 13 is a cross section of the compressed air conduits of the switch board action illustrating the electro-pneumatic valve associated therewith.

As appears in the course in of the following description, use is made, in the improved 60 pipe organ control, of the cipherless device disclosed in my co-pending application #2, filed Feb. 6, 1924, Serial Number 690, 958. The cipherless device is not indispensable to the operation of the pipe organ control inasmuch as the organ may be operated without it and also it may be used in connection with pipe organs of types other than that herein disclosed, but because of the fact 65 that it performs an important function in a 70 number of cases a description thereof appears here quite properly.

Before describing the operation, the details of construction must first be understood and are described under the following heading: The keyboard and relays, the chest action, the switch board action, and the cipherless device. Taking these in the order 75 named attention is first directed to

The keyboard and relays.

Only enough of the keyboard is illustrated to make the action readily understood. The 80 keys 1, 2, 3, 4, 5, 6, 7 and 8 comprise an octave and control corresponding organ pipes 9, 10, 11, 12, 13, 14, 15 and 16. The keys and 85 corresponding pipes are lettered C, D, E, F, G, A, B, C, according to the notes that they are adapted to produce.

According to the showing as it now stands in Figure 1 only pipes 13, 14, 15 and 16 may be sounded by the operation of corresponding 90 keys 5, 6, 7 and 8 for the reason that only the switch board action 17 has been rendered active by the depression of the finger 18. The other switch board 19 is controlled by the finger 20. These parts constitute 95 what seemingly are commonly known as “stops”, the one being diapason, the other 100 flute.

Technically the so-called stops 18 and 20 are known as fingers, and in practice they consist of electric switches arranged on the 105 console of the organ within ready reach of 110

the organist so that by merely flipping one or any combination of the fingers down or up he may bring into play or cut out such parts of the organ which said fingers control. For example, flipping the finger 13 down operates the switch board 17 and brings that combination of organ pipes into play commonly known as diapason. Flipping the finger 20 down would have the 10 same effect in respect to that combination of pipes which when played will have the sound of a flute.

The reader will readily understand that the number of pipes embraced by the stop 15 diapason is not limited to the four pipes embraced by the brackets under that heading in Figure 1. This is also true of the number of pipes that operate to make the 20 sound of a flute, although diapason, being one of the principal stops of the organ, will embrace more pipes than the flute. The four pipes in each case are taken merely as an example to illustrate the action, and with this preface the description of the keyboard 25 and relays is now proceeded with.

Each respective key has a relay 21, 22, 23, 24, 25, 26, 27 and 28. In the particular organ disclosed there is a relay for each 30 key. (Fig. 1). Figure 6 illustrates one of the relays in detail, and the description of 35 this one will suffice for all because they are identical. The relay chosen for description is the relay 25 inasmuch as it is operated by the key 5 which happens to control the first pipe 13 under the stop diapason.

A base 29 carries the individual relays 40 which are mounted on the same, one after another (Fig. 2), so that the connections with the respective keys may readily be 45 made. In the event that all the relays necessary for one manual call for a base too long to fit the space provided, bases of sufficient combined lengths may be employed. An electro-magnet 30 (Fig. 6) is adapted 50 to attract the metallic disk or armature 31 of the transfer valve which includes the external valve 32. Both valves are carried by a stem 33 which is releasably movable in the passage 34 which extends vertically through the base 29.

The upper side of the disk 31 is faced 55 with leather 35 to prevent sticking to the poles of the magnet 30. The lower side of the disk is similarly faced at 36 to provide a good closure member for the passage 34. No guide is necessary for the stem 33. The valve 32 is adjustable on the end of the stem by means of a button 37 which may be turned on the threaded end of the stem. 60 The valve 31 works between the top of the base and the under side of an insulating bridge 38 by which the electro-magnet 30 is carried.

This bridge is supported from the base 65 by spacers 39 which run full length of the

relay base (Fig. 2). The insulating bridges 38 are applied wherever necessary. The electro-magnet 30 is energized by the depression of the key 5 (Fig. 1). This key has a contactor 40 which is then adapted to engage a contact 41. This contact 41 has connection with the positive wire 42 which is common to all of the keys in the organ. 70

The wire 42 runs to the positive pole of a battery 43, the negative pole of which has 75 connection through a wire 44 with a bus 45 which may be common to the electro-magnets 30 of all of the relays. A depression of the key 5 will therefore cause current to flow from the positive pole of the battery 43, over wire 42 to the contact 41, contactor 40 over a wire 46 to the magnet 30 and from the magnet over a wire 47 to the bus 45 whence it returns to the negative pole of the battery by way of the wire 44. 80

A housing 48 encloses all of the relay magnets. This housing constitutes a conduit. The conduit runs lengthwise of the base 29 as shown in Figure 2. Air under compression is present in the conduit 48. The relay 90 conduit 48 is supplied by the main air conduit 49 (top of Fig. 1) but the cipherless device 50 is interposed in the connection between the two. Upon energization of the magnet 30 (Fig. 6) air will flow from the 95 conduit 48 into the passage 34 and thence into the duct 51 this action occurring upon the lifting of the valve 31 which opens the passage 34 seats the external valve 32 against the base 29 thus intercepting communication 100 between the passage 34 and the atmosphere.

Air from the duct 51 (Fig. 6) causes the bellows or pneumatic 52 to expand until the contactor 53 engages the wires of a contact block 54, thereby closing a circuit 105 which is entirely independent of the one previously described in connection with the key 5.

A block 55 forms the under part of the pneumatic, this block being fastened to the 110 base 29 and having an opening in continuation of the duct 51. A flexible piece of leather 56 encloses three sides of the pneumatic, the fourth or rear side 47 providing a hinge on which the top 52 moves in the 115 aforesaid expanding action. A spring 58 keeps the pneumatic collapsed when the external valve 32 is open. The movement of the top 52 is limited by a yoke 59 which carries a felt pad 60 on the under side. 120 This yoke is supported by staffs 61 which are threaded on the ends to respectively screw into the base 29 and to take pairs of buttons 62 which function to support the yoke in the proper position.

A bus 63 is attached to one side of the yoke and has a flexible connection 64 with the contactor 53. The contactor is secured to the top 52 by means of a screw 65, and another screw 66 is so mounted on the top 125

52 and passes through the contactor 53 in such a manner as to allow the latter to be adjustable into a lower or higher plane with respect to the contact wires of the block 54

5 mentioned before. The bus 63 is common to all contactors 53 of the relays in the entire organ, not only those of the key board in Figure 1.

The block 54 carries four contact wires 10 67, 68, 69 and 70. The number of contact wires illustrated is arbitrarily chosen to show that the block carries a plurality of wires. The number that it actually carries may be six, eight, twelve, etc. in fact there 15 will be as many contact wires as there are organ pipes subject to the control of the individual key 5. The depression of the key 5 may cause the simultaneous sounding of a number of organ pipes. However, all of 20 the contact wires may not become active with each depression of the key 5. Some may be cut out of action and this is done by one or the other of the switch board actions 17 and 19.

25 The chest action must be described next in order that the ultimate function of the relay 25 may be understood. Use is made of the contact wire 67 only to illustrate the action of the relay. This contact has connection 30 through a wire 71 with a contactor wire 129 of the plate 74 in the switch board 17, a wire 73 connecting this plate with one side of an electro-magnet 72. A battery 75 has one wire 76 which is common to all 35 of the electro-magnets of the chest action, and another wire 77 connecting with the bus 63 described in connection with Fig. 6. The depression of the key 5 therefore causes the contactor 53 to engage the wire 67 so 40 that current flows from the positive pole of the battery 75 over wire 77 to the bus 63, over wire 64 to the contactor 53, contact wire 67 and wire 71 to the contactor 129, plate 74 and wire 73 to the electromagnet 72, returning via the common wire 76 to the negative pole of the battery.

Let the reader imagine one or more of the contact wires 67, 68, etc. of the relay 25 as controlling electro-magnets 79 of organ pipes other than those that come under the control of the switch board 17. For example the contact 68 may be connected by means of a wire 78 (dotted lines) with such contactor wire and contact plate of the switch board 19 that control the sounding of the pipe 12. This pipe is one which when sounded will produce the note of a flute. Inasmuch as the feed wire 80 of this electro-magnet can receive no current due to the 50 open position of the finger 20 and the consequent inoperativeness of the switch board 19, no action will result in the pipe 12 upon operation of the key 5. It is only when the organist wishes to include the playing of the 55 flute by flipping the finger 20 down that the

particular contact 68 becomes operative upon the depression of the key 5. A similar principle prevails in respect to the other contacts 69 and 70.

Before proceeding with the description of 70 the chest action attention is directed to Figure 3 which shows the contact wire block 54 in detail. The block has a number of parallel slits 81 in which the contact wires may move up and down upon engagement 75 and disengagement of the contactor 53. The inner ends of the wires are bent at 82 and forced through the bottom of the block 54 where connections of such wires as 71, 78 (Fig. 6) are made. The bent portions of 80 the wires occur in a transverse groove 83 which is occupied by a key 84 when the block is mounted in place. The key holds the wires against loosening or coming out. The key is part of a bridge 85 which is mounted 85 on standards 86. A depending part 87 of the bridge has openings 88 through which the aforesaid wires pass.

Reverting now to the chest action: The pipe 13 and others have communication with the conduit 89 (Figs. 1 and 7) of the chest action through orifices 90 which are adapted to be closed from the inside by felt buttons 91. Each of these buttons is carried by a puff 92 which is mounted on a plate 93 running lengthwise of the conduit. This plate is affixed to a support 94 (Fig. 7). The button 91 is held up against the orifice 90 by a spring 95, the spring performing this function as long as there is an equalization 95 of air pressure on both sides of the puff. The electro-pneumatic valve 72 controls this equalization of air pressure.

Air under compression is supplied to the conduit 89 by the main conduit 49 in Figure 1, the cipherless device 96 being interposed in the connection between the two. The electro-magnet 72 (Fig. 7) mentioned above and in connection with Figure 1, is carried by the valve base 97 which has a cover 98. The base and cover are made of lead or other suitable non-magnetic material so that the flap valve 99 will not adhere to the poles of the magnet after having been attracted thereby. The flap valve is loosely held by a link 100 which attaches to the cover or valve chest at a convenient place. The valve normally rests on the inner end of a vent tube 101 so as to prevent the escape 105 of air to the atmosphere and provide for the conduction of air from the conduit 89 through the passage 102, ports 103 and 104 and passage 105. The vent tube 101 is threaded and has a screw driver slot 110 so that it may be adjusted. The purpose in making the vent tube 101 adjustable is that the valve 99 will be made to respond more or less promptly to the energization 115 of the electro-magnet 72 above.

Screws 106 secure the valve chest or cover 130

98 to the base 97. One of these screws passes through a solid part of the cover (see right of Fig. 7) while the other passes through a notch 107. Screws other than 106 are used to secure the base 97 beneath the passage 89, holes 108 (Fig. 8) being used for this purpose. Gaskets 109 disposed to tighten the joints between the various connecting surfaces of the pneumatic 10 valve as shown in Figure 7.

The conduit 89 of the chest action, like other similar conduits and in fact most of the parts of the control mechanism is composed of pieces of wood so screwed together 15 that separation is easy for purposes of repair or replacement of parts. The pieces, in respect to the conduit 89, consist of a top 110, sides 111 and a bottom or base 112. It is to this bottom that all pneumatic valves, 20 like the valves 98 are secured. The bottom 112 is held in place against the sides by means of long wood screws 113 which carry compression springs 114.

The switch board action has already been 25 described in part. It is cited as a representative type of switch board necessary for the proper operation of the relay and chest actions. To this end it is claimed as an element of the combination, although the electric and pneumatic action controlling the 30 switch board action is claimed as a part of this invention. Take the switch board action 17 as an example. The action 19 is identical therewith and therefore the description of the one will suffice for the other.

The upright portion of the switch board carries a plurality of contact plates of which the plate 74 has already been described. Other plates 115, 116 and 117 are connected 40 by means of wires 118, 119 and 120 with one side of the electro-magnets 121, 122 and 123 of the organ pipes 14, 15 and 16. The complementary wires 124, 125 and 126 of contactors 140, 141 and 142, which cooperate 45 with said contact plates, extend to the contact wires 191, 192 and 193 of relays 26, 27 and 28 (Fig. 1). The electro-magnets 121, 122 and 123 all have connection 50 with the common wire 76. A depression of any one of the keys 6, 7 and 8 of respective relays will produce a response in pipe 14, 15 or 16 similar to that produced in the pipe 13 by the depression of the key 5.

Other contact plates and contactor wires 55 in the switch board action 17 will be connected with such other parts of the chest action and key board as complete the control of the stop diapason. The actual showing of such connections is regarded as unnecessary because when the reader understands the action following the depression 60 of the key 5 he understands the action following the depression of any other key. Reference is now made to Figures 11, 12 and 65 13. Mounted in brackets 127 in front of

the contact plates is a tracker 128 which is adapted to rock on pivots 129 upon a downward pull on the shaft 130 and link 131 by the compression of the bellows or pneumatic 132.

The shaft 130 has connection with an arm 133 which extends from the tracker, a button 134 on the threaded end of the shaft serving to make certain necessary adjustments between the shaft and the arm. Another arm 135, extending from the tracker, serves as the connection for one end of a spring 136 the other end of which is connected to an arm 137 which is fixed in the switch board panel. The purpose of 80 the spring 136 is to keep the tracker 128 up, as shown for example by the tracker in the switch board action 19.

The tracker 128 has a plurality of contactor wires of which 139, 140, 151 and 142 85 have been mentioned before. These connect with the plates 74, 115, 116 and 117 also mentioned before. There are other contactors on the tracker but these need not be specifically mentioned. The contactors 90 have individual connection with certain ones of the relay contact wires as shown in Fig. 1. It is not until the tracker 128 is rocked into the position shown in Figure 1 that the contactors 139, etc., move into engagement 95 with the plates 74, etc., and thus complete a circuit.

The rocking of the tracker 128 is accomplished by flipping one of the fingers on the console of the organ down. In the present 100 instance it is the finger 18 that causes the operation of the switch board action 17. This finger has a contactor 143 which is engageable with the contact 144 from which a wire 145 extends to one side of an electro- 105 magnet 146 in the compressed air conduit 147. The return wire 148 reaches to the negative pole of the battery 149 from the positive pole of which a wire 150 extends to the finger 18. The wire 150 is common 110 to a number of electrical appliances, as appears farther on. The reader will now see that the closure of the switch 18, or to use the foregoing expression to flip the finger 18 down, causes the energization of the 115 magnet 146 of the switch board action 17.

This energization attracts the flap valve or armature 151 so that the port 152 is closed and the vent tube 153 is opened to atmosphere. The port 152 furnishes 120 communication between the passage 154 and the interior of the cover or valve chest 155 when the flap valve 151 rests on the tube 153 as shown in Figure 13. The port 152 and another port 156 are formed in the base 157 125 of a pneumatic valve which the reader will recognize at once as being similar to the valve 98 in Figure 7. The construction and operation are identical.

The port 156 has communication through 130

a duct 158 (Figs. 1 and 13) with the chamber 159 of a puff 160. This puff includes a felt button 161 which is situated in an exhaust passage 162 provided with exhaust openings 163.

Under that condition wherein the electro-magnet 146 is deenergized air under pressure from the conduit 147 reaches the chamber 159 and forces the puff 160 out so that the double escapement valve 164, 165 (Fig. 1) severs communication between the bellows chamber 166 and the exhaust passage 162. The position corresponding with this description is shown in the case of the switch board action 19. Upon energization of the magnet 146 the passage of compressed air from the conduit 147 to the chamber 159 is interrupted thereby permitting an exhaust of air from behind the puff 160 to the atmosphere through the vent tube 152. At the same time, the valve 165 closes the opening 167 between the chamber 166 and passage 162.

The pressure of air from the conduit 147 entering the chamber 166 through the tube or other connection 168 thereupon causes the depression of the bellows 132 so that the tracker 128 is rocked and the contactor wires 139, etc., brought into engagement with the plates 74, etc. The opening 167 has communication through a duct 169 with the inside of the bellows 132, and when the valve 164 closes the right side of the opening 167 the equalization of air pressures inside and outside of the bellows permits the spring 136 to keep the tracker 128 in the upright position shown in Figure 11.

Upon closure of the opening 167 by the valve 165 the pressure outside of the bellows 132 predominates so that the bellows is depressed against the tension of the spring 136. The air inside of the bellows exhausts through the opening 167 into the passage 162 thence to atmosphere via the openings 163. The release of the finger 18 causes the deenergization of the magnet 146 so that air from the conduit 147 again forces the puff 160 out, reversing the position of the valves 164, 165 of the switch board action 17 thereby again causing an equalization of pressures on both sides of the bellows with the result that the tracker 128 rocks back.

The cipherless device, as explained above is the subject matter of a co-pending application for letters patent but is incorporated herein because of its important function of eliminating ciphers in the chest action 89 and also eliminating any obstructions that might impair the functioning of the transfer valves of the electro-pneumatic relays. It is necessary to provide two separate cipherless devices 96 and 50 for the respective purposes. In practice there will be one cipherless device for each chest action and also one for each relay action.

The cipherless device 50 receives air from the main conduit 49 by way of a tube 170 and delivers the air to the conduit 48 by way of a tube 171. Similarly, the cipherless device 96 receives air from the conduit 49 by way of the tube 172 and delivers the air to the chest action 89 by way of the tube 173.

It sometimes occurs in the playing of the organ that an obstruction enters the space 75 between the felt button 91 and its seat against the top 110 of the air conduit 89 and thereby hold the orifice 90 open. Such obstruction may consist of a roll of lint, dust, etc. The effect is that air continues to pass 80 through the orifice 90 so that the corresponding organ pipe continues to sound regardless of the fact that the key which controls it has long been released.

The continued sounding or droning of the 85 organ pipe is known as a "cipher." Inasmuch as the button 91 is not readily accessible, it becomes necessary to stop playing the organ until the chest action can be opened to remove the obstruction. By use of the 90 cipherless device, the chest action can be cleared of the obstruction, or if necessary, the entire chest in which the cipher has occurred may be cut out thereby making it unnecessary to cease playing the organ entirely.

A rectangular box furnishes the housing and support for a combined cut-out and escapement valve 174 and 175 and a combined magnetic release valve and escapement valve 176 and 177. The former are carried by a rod 178 which is suspended from a puff 179. The latter are carried by a rod 180.

The respective valves control passages 105 181 and 182, the former communicating with the tube 173, the latter with a duct 183 which extends to a place above the puffs 179. Both passages extend through from the interior of the cipherless device to 110 the atmosphere. An electro-magnet 184 is adapted to attract the release valve 176 upon depression of a switch 185 which closes a circuit from the battery 149 over common wire 150, wire 186, switch 185, 115 whence the current returns to the negative pole of the battery via wire 187. This wire has connection with the negative return wire 148 which is described in connection with the switch board 17.

According to the position of the cipherless device 96 in Figure 1 the pressure of air holds the puff 179 up, this by virtue of the fact that the puff is of larger area than the valve 174. The valve 175 is therefore held closed so that no air may escape to atmosphere. The passage 181 is therefore held open to the tube 173 and air passes to the chest action 89. The magnetic release 125 valve 176 closes the passage 182 by gravity 130

and there is therefore no air pressure above the puff.

A depression of the switch 185 will cause the energization of the magnet 184 so that the release valve 176 is attracted. The valve 177 closes the atmosphere end of the passage 182, and the opening of the inner end of this passage permits air to reach the upper side of the puff 179. The consequent equalization of air pressures on both sides of the puff permits the valves 174 and 175 to fall by gravity. The cut out valve 174 therefore severs communication between the main conduit 49 and the tube 173 so that no compressed air can reach the chest action and the valve 175 being opened, such compressed air as the chest 89 contains is exhausted. If it is desired to cut the chest action out entirely the organist must let the switch 185 remain closed. Should he desire to clear the chest action of the aforesaid obstruction, a rapid opening and closing of the switch 185 will produce a succession of impulses of air in the chest action 89 which will have the effect of blowing out such obstruction as prevents one of the buttons from seating.

The operation may now be readily understood in the light of the foregoing description. The reader can readily imagine the console of an organ as being equipped with a plurality of fingers such as 18 and 20 (Fig. 1) each of which being adapted to bring into operation such ones of the organ pipes as will produce the sounds classified under the legends on the fingers. One or more of these fingers must be slipped down before the organ will play.

Assume the finger 18 to have been slipped down. Current flows from the positive pole of the battery 149 to the common wire 150, through the contactor 143 to the contact 144, over wire 145 to the electro-magnet 146, whence it returns via wire 148 to the negative pole of the battery. The energization of the magnet 146 causes the shifting of the escapement valves 164, 165 (compare with the switch board 19) so that there is a release of pressure inside of the bellows 132 and a preponderance of pressure on top. The bellows is therefore depressed, causing the rocking of the tracker 123 and the engagement of its carried contactor wires 139, etc. with the contact plates 74, etc. The engagement of the contactor wires with the plates produce only the partial closure of the circuits in which said wires and plates are situated. The remainder of the circuits are closed when the organ keys are depressed.

Assume the organist as depressing the key 5 which will sound the key G in the stop "diapason." The engagement of the contactor 40 will cause the passage of current from the positive pole of the battery

43 to the common positive wire 42, through the contact 41 and contactor 40 to the wire 46, through the electro-magnet 30 and over wire 47 to the negative bus 45 whence it returns to the negative pole of the battery 43 via wire 44. The resulting energization of the magnet 30 of the relay 25 attracts the transfer valve 31 (Fig. 6) so that air from the relay conduit 48 is permitted to pass into the duct 51 and thereby extend 75 the bellows 52.

The extension of the bellows 52 will bring the contactor 53 into engagement with the contactor wires 67, etc. and close a circuit from the positive pole of the battery 75 over wire 77 to the positive bus 63, over wire 64 to the contactor 53, wires 67 and 71 to the switch board contactor 139 and contact plate 74 and over wire 73 to the chest action electro-magnet 72 whence it continues via wire 76 to the negative pole of the battery.

This energization of the magnet 72 causes the shutting off of air from the conduit 89 to the interior of the puff 92 (Fig. 7) by 90 virtue of the fact that the flap valve 99 is attracted and closes the port 103. The air in the passage 89 thereby causes the depression of the puff 92 so that the button 91 opens the orifice 90. The escape of air at 95 the orifice causes the sounding of the corresponding pipe 13. As soon as the organist releases the key 5 the breaking of the circuit through the electro-magnet 30 permits the valve 31 to fall back and the bellows 104 52 to collapse. The breaking of the circuit of the magnet 72 at the contactor 53 and wire 67 causes the flap valve 99 (Fig. 7) to fall back and reopen the port 103 so that the pressure of air on both sides 105 of the puff 92 is equalized. The spring 95 thereupon causes the re-seating of the button 91 against the inlet to the orifice 90.

It sometimes happens that a roll of lint will get between the button 91 and the top 110 of the chest action and thereby prevent the button from seating. The continued passage of air into the pipe causes what is known as a "cipher." The cipherless device 96 is intended to cause the removal of 115 this objection by producing a succession of air impulses in the chest action and thus dislodging the lint.

This succession of impulses is produced by opening and closing the switch 185. A 120 closure of the switch will cause the energization of the magnet 184, whereupon the attraction of the release valve 176 will cause an equalization of air pressure on both sides of the puff 179. The cut-out and escapement valves 174, 175, which are carried by the puff, will then fall by gravity so that the valve 174 cuts off communication between the main conduit 49 and the tube 173 which leads to the chest action. An 130

opening of the switch will cause a reversal of operation, the result being the succession of air impulses mentioned before.

The action of the cipherless device 50 is identical with that of the device 96, the only difference being that the device 50 functions in respect to the relay conduit 48. A closure of the switch 188 will cause an energization of the electro-magnet 189 and produce the same result in respect to the valves 190, 191 and 192, 193. A series of openings and closures of the switch 188 will produce corresponding impulses of air in the conduit 48 and thereby clear the transfer valves of the relays of any obstruction that might be preventing one or more of them from seating. The description of the action attending the depression of the key 5 is representative of the action following the depression of any of the keys. The switch board action 19 comes into operation upon flipping down of the finger 20, such pipes as produce the sound of a flute then being made operative.

In conclusion it is desired to point out that all of the vital working parts of the organ control are readily accessible for purposes of replacement and repair. This is due to the fact that any one of the various conduits may readily be taken apart. The reader will observe that the cipherless devices are separable in all respects, that is to say either the front or back may be taken off so that the interior may readily be reached. This feature of accessibility is of great value.

While the construction and arrangement of the improved pipe organ control as herein described and claimed is that of a generally preferred form, obviously modifications and changes may be made without departing from the spirit of the invention or the scope of the claims.

I claim:—

- 45 1. An organ control comprising the combination of a chest action having an organ pipe, an air conduit, a button to stop the passage of air through said pipe and an electromagnet to control the air pressure for said button; an electric circuit embracing said electro-magnet including a relay, a bellows in said relay having a contactor adapted to complete part of said circuit, a transfer valve 31 normally in position to open the bellows to atmosphere and close off the conduit, an operating magnet for said valve, a key adapted to energize the magnet and shift the valve to close off the atmosphere, cause the inflation of said bellows from said conduit and the operation thereof to cause the the partial closure of the aforesaid circuit, and a switch board having a contactor and contact adapted to be in engagement to complete said circuit.
- 55 2. An organ control comprising the com-

bination of a main air conduit, a chest action having a pipe and a control button therefor, an electro-magnet adapted to control the air and cause a movement of said button, a relay having a transfer valve 70 adapted to control the passage of air from said conduit, a bellows in respect to which said air is controlled, a magnet for actuating the valve, a key adapted upon depression to energize the magnet and thereby 75 cause the expansion of said bellows, an electrical circuit adapted to be partially closed by said bellows and including the chest action electro-magnet, and a switch board through which said circuit is completed 80 thereby energizing said electro-magnet and causing the sounding of said pipes.

3. An organ control comprising the combination of a main air conduit, a chest action receiving air from said conduit, said chest action having a pipe, a relay receiving air from said conduit, a key to operate the relay, and means in the chest action operated by the relay upon energization thereof by the depression of the key to cause the sounding 85 of said pipe by air from said conduit, said relay being operated in part by air from said conduit.

4. An organ control comprising the combination of a main air conduit, a relay having a bellows adapted to be expanded by air from said conduit, a chest action having a pipe adapted to be operated by air from said conduit, a button to control the passage 95 of air to said pipe, an electro-magnet controlling the pressure of air in respect to said button, means operated by said bellows to partly complete a circuit through said magnet, means controlling the passage of air from said conduit to the bellows, and a 100 key for operating said controlling means.

5. An organ control comprising the combination of a chest action having an electro-magnet, a relay having a contact in electrical connection with said magnet, a pneumatically movable contactor adapted to engage said contact, means for controlling the movement of air for the operation of said contactor, and an organ key for operating 110 said controlling means.

6. An organ control comprising the combination of a chest action having an electro-magnet, a relay having a contact in electrical connection with said magnet, a compressed air conduit, a bellows adapted to communicate with said conduit, a valve controlling said communication, a contactor carried by the bellows to engage the contact upon admission of air, means to raise the valve and thereby permit such admission, and a key 115 to control the operation of said raising means.

7. An organ control comprising the combination of a chest action having an electro-magnet, a relay having a contact in elec- 120

- trical connection with said magnet, a compressed air conduit, a bellows adapted to communicate with said conduit, a contactor carried by the bellows adapted to engage the wire upon expansion of the bellows, a gravity-held valve severing communication between the conduit and bellows, an electro-magnet adapted to raise the valve to a communicating position, and a key having circuit controlling means for energizing said electro-magnet upon depression thereof to cause the partial completion of a circuit between the relay and chest action electro-magnet.
15. 8. An organ control comprising the combination of a chest action having an electro-magnet, a relay having a contact in electrical connection with said magnet, a compressed air conduit, a bellows adapted to communicate with said conduit, a contactor carried by the bellows adapted to engage the wire upon expansion of the bellows, a gravity-held valve severing communication between the conduit and bellows, an electro-magnet adapted to raise the valve to a communicating position, a key having circuit controlling means for energizing said electro-magnet upon depression thereof to cause the partial completion of a circuit between the relay and chest action electro-magnet, a switch board having contact means for completing the circuit through said last electro-magnet, and means for operating the switch board to close said contact means.
30. 9. An organ control comprising the combination of a chest action having an electro-magnet, a relay having a contact with a wire extending through said magnet and forming part of a circuit embracing said magnet, a block by which said contact is carried, a bellows situated beneath the block and carrying a contactor which is movable beneath said contact, a compressed air conduit adapted to furnish air for the expansion of said bellows, a metallic valve normally gravitated to a closing position, an electro-magnet situated above said valve, and an organ key having a switch for controlling the energization of said magnet and of said valve.
45. 10. An organ control comprising the combination of a chest action having an electro-magnet, a relay comprising a base, a bellows mounted on the base and having a movable portion, a contactor carried by the movable portion, a contact situated above said contactor having a conductor extending to and forming part of an electrical circuit for said electro-magnet, a compressed air conduit adapted to furnish air to said bellows, a metallic valve gravitated to a closing position, an electro-magnet adapted to attract said valve and admit air to the bellows for the partial closure of said circuit, and a key for controlling the operation of said relay electro-magnet.
55. 11. An organ control comprising the combination of a chest action having an electro-magnet, a relay for controlling the energization of said magnet comprising a base, a valve gravitated to a closing position in respect to a passage and duct in said base, a bellows with the interior of which said duct communicates, an electro-magnet adapted to attract said valve, a compressed air conduit housing the electro-magnet and valve furnishing air to the duct and bellows when said passage is uncovered, a contact having a conductor leading to and forming part of a circuit embracing the chest action electro-magnet, a conductor carried by the bellows engageable with said contact to complete part of said circuit, and an organ key having switch means to control the energization of the relay electro-magnet.
65. 12. An organ control comprising the combination of a chest action having an electro-magnet, a relay for controlling the energization of said electro-magnet comprising a base having a duct communicating at one end with a transverse passage in the base, a compressed air conduit communicating with one end of the passage, a valve gravitated to a closing position on said end of the passage, an electro-magnet situated in said conduit adapted to attract said valve, an external button associated with said valve then closing the other end of said conduit so that air may enter the duct, a bellows with which the other end of said duct communicates, a contact having a conductor extending to and forming part of an electrical circuit embracing said chest action electro-magnet, a contactor carried by the bellows adapted to engage said contact and complete part of said circuit, and an organ key having a switch adapted to energize the relay electro-magnet upon depression.
75. 13. An organ control comprising the combination of a chest action having an electro-magnet, a relay for controlling the energization of said electro-magnet comprising a base having a transverse passage and a duct, electrical contact means forming part of a circuit embracing said electro-magnet, a bellows in communication with said duct carrying one of the elements of said contact means, a double valve situated in said passage closing one end and leaving the other open to atmosphere, a compressed air conduit adapted to communicate with the duct, and means for reversing the position of said valve to close the atmosphere end of said passage and open the other end into communication with the conduit.
85. 14. An organ control comprising the combination of a chest action having a plurality of electro-magnets, a relay base, a compressed air conduit extending along the base, a plurality of relays mounted on the base one for controlling the energization of

- each electro-magnet and each relay comprising a bellows adapted to communicate with the conduit, electrical contact means associated with each bellows adapted upon 65 operation to complete part of a circuit for the respective electro-magnets, a valve for each relay normally preventing the passage of air from the conduit to the bellows, a plurality of electro-magnets housed by the 70 conduit one for each valve, and a plurality of organ keys each having a switch adapted to energize a corresponding relay electro-magnet to lift the corresponding valve and so cause the operation of the bellows.
15. An organ control comprising the combination of a chest action having an electro-magnet and a button controlling a pipe orifice, said chest action including a conduit having a separable top in respect 75 to which the button operates and a separable bottom by which said magnet is carried, a relay for controlling the energization of said magnet, comprising a base, a bellows having electrical contact means 80 adapted to close part of the circuit embracing said magnet, an electro-magnet and valve mounted on the base for controlling the passage of air through said bellows, and a compressed air passage mounted on 85 the base to house said magnet and valve, said conduit being removable to permit access to said magnet and valve. 90
16. An organ control comprising the combination of a chest action having a plurality of electro-magnets, a switch board action having contact means, and a plurality of individually organ-key operable relays for controlling the energization of said electro-magnets, each relay comprising a pneumatically operated contactor and a plurality of contact wires for each contactor having connection with predetermined ones of said electro-magnets through the contact means of said switch board action, said switch board action being adapted for cutting out desired ones of said contact wires. 95
17. An organ control comprising the combination of a chest action having a plurality of electro-magnets, organ pipes having air control buttons operable by the influence of said electro-magnets, a relay having a pneumatically operated contactor, a contact block having a plurality of contact wires connectible with predetermined ones 100 of said electro-magnets, an organ key upon depression of which said contactor is brought into engagement with said wires and complete partial circuits embracing said magnets, and a switch board action through which said circuits are adapted to be completed said action having contact plates to which only predetermined ones of 105 said electro-magnets are connected thereby permitting the closure of circuits only 110 through connected electro-magnets upon depression of said organ key. 115
18. An organ control comprising the combination of a chest action having a plurality of pipes, a control button for each, an electro-magnet for controlling each button, a relay having a plurality of contact wires individually connectible to predetermined ones of said electro-magnets, a bellows, a compressed air conduit for supplying air to said bellows, a valve normally severing communication, an electro-magnet adapted to attract said valve so that air may reach the bellows, an organ key having switch means for energizing said relay 120 electro-magnet to thereby attract the valve, a contactor carried by the bellows then engaging said wires to complete parts of circuits through said chest action electro-magnets, and a switch board action through which said circuits are adapted to be completed, said switch board having contact plates to which certain ones of the chest action magnets are connected and contactor wires to which certain relay contact wires are connected adapted to engage said plates. 125
19. An organ control comprising the combination of a chest action which comprises an air conduit having orifices leading to organ pipes, a puff having a button for closing each orifice, a spring for holding each button against the orifice, an electro-magnet for each puff having a flap valve for controlling a duct furnishing communication between the conduit and the interior of the puff, a relay having a plurality of contact wires individually connectible with the respective electro-magnets, a contactor adapted to engage said wires and complete parts of circuits through said electro-magnets, and a switch board through which predetermined ones of said circuits may be completed thereby causing the energization of such electro-magnets the circuits of which are completed through the switch board upon engagement of said contactor 130 with said wires. 135
20. An organ control comprising the combination of a chest action which consists of an air conduit having an orifice leading to an organ pipe, a puff having a button to control said conduit, an electro-magnet, a base by which said magnet is carried having a pair of ports one communicating with the conduit the other with a duct leading to the interior of the puff, a cover plate for said ports providing a valve chamber into which said ports discharge, a vent tube carried by the cover, a flap valve covering said tube and thereby providing for an equalization of air pressures on both sides of the puff, a spring inside of the puff pressing the button against the orifice, and an organ key operated relay having contact means 140 145 150 155 160 165 170 175 180 185 190 195 200 205 210 215 220 - adapted to energize said electro-magnets for the attraction of the flap valve to sever air communication with the interior of the puff, the air in the conduit thereby depressing the puff and causing the opening of the orifice.
21. An organ control comprising the combination of a chest action having a compressed air conduit with an orifice, an organ pipe fitted in said orifice, a plate mounted on a support inside of said conduit, a puff carried by said plate having a button, a spring inside of the puff pressing the button against the orifice, a valve base carried by the conduit and a pair of ports respectively communicating with the interior of the conduit and with a duct leading to the interior of the puff, an electro-magnet carried by the base having pole pieces exposed to the bottom of the base, a hollow cover fitted over the base providing a valve chest, a vent tube carried by the cover, a flap valve gravitating on the vent tube, a link by which the valve is loosely carried, and an organ key operated relay having contact means to control the energization of said electro-magnet upon energization of which said flap valve is attracted against one of the ports to sever communication of the conduit and to open communication between the interior of the puff and the atmosphere through said vent tube.
22. An organ control comprising the combination of a chest action having a compressed air conduit with an orifice, an organ pipe fitted in said orifice, a plate mounted on a support inside of said conduit, a puff carried by said plate having a button, a spring inside of the puff pressing the button against the orifice, a valve base carried by the conduit and a pair of ports respectively communicating with the interior of the conduit and with a duct leading to the interior of the puff, an electro-magnet carried by the base having pole pieces exposed to the bottom of the base, a hollow cover fitted over the base providing a valve chest, a vent tube carried by the cover, a flap valve gravitating on the vent tube, a link by which the valve is loosely carried, an organ key operated relay having contact means to control the energization of said electro-magnet upon energization of which said flap valve is attracted against one of the ports to sever communication of the conduit and to open communication between the interior of the puff and the atmosphere through said vent tube, and means by which said vent tube may be adjusted in respect to the electro-magnet thereby requiring a varying amount of energizing current to attract said valve.

GUSTAV H. KLOEHS.
